UNITED STATES PATENT OFFICE.

DAVID E. SCHAFER AND JOHN W. SCHAB, OF COLUMBUS, OHIO.

SIGN.

Application filed April 30, 1924. Serial No. 710,049.

To all whom it may concern:

Be it known that we, DAVID E. SCHAFER and JOHN W. SCHAB, citizens of the United States of America, residing at Columbus, in the county of Franklin and State of Ohio, have jointly invented certain new and useful Improvements in Signs, of which the following is a specification.

Our present invention relates generally to signs and more particularly to signs adaptable to advertising and other purposes and having changeable letters, characters and the like. Our primary object is the provision of a sign of this type which will be attractive and effective in use, which may be readily applied upon buildings, motor vehicles and the like, and which will be simple and inexpensive both as to first cost and upkeep.

Generally speaking, our invention proposes a sign including an outer rigid frame, an inner frame interfitting the outer frame, and a series of interchangeable sign panels within the inner frame in any desired relation to form the reading matter of the sign, the inner frame having means to hold the sign panels, and the outer frame having means to hold the inner frame securely and safely in place and at the same time in such manner that it may be easily and quickly inserted in and removed from the outer frame.

With the above objects and general statement in mind, our invention resides in the features of construction, arrangement and operation to be now described with respect to the accompanying drawings in which—

Figure 1 is a side view illustrating one of the many practical applications of the invention,

Figure 2 is a front elevation of the outer frame of our improved sign with the remaining parts removed,

Figure 3 is a side view thereof,

Figure 4 is an enlarged vertical section through the lower portion of one side of the outer frame,

Figure 5 is a vertical sectional view taken on line 5—5 of Figure 4,

Figure 6 is an enlarged section through the other lower side portion of the main frame,

Figure 7 is a vertical section taken through the main frame at a point inter-

mediate its ends, showing the application of a bracing member thereto.

Figures 8 and 9 are respectively a side view and horizontal section showing one of the spring holders carried by the outer frame for the support of the inner frame,

Figures 10 and 11 are respectively a front elevation and side view of the inner frame,

Figures 12 and 13 are enlarged vertical sections taken on line 12—12 of Figure 10 showing the parts in different positions,

Figure 14 is a vertical transverse section through the complete sign including the inner and outer frames and the panels.

Figures 15 and 16 are respectively a front elevation and side view of a slightly modified form of inner frame.

Referring now to these figures our invention proposes a sign including an outer frame having end uprights 10 and 11, both of which have inner grooves extending therealong and the end piece or upright 11 being slotted through as seen at 12 in Figure 3 and provided on its front side with spaced bosses 13. These end pieces or uprights 10 and 11 which may be provided intermediate their ends with one or more lugs 14 apertured to receive fastening screws or other members for securing the frame to a wall or for instance to the side of the body 15 of a motor vehicle as in Figure 1, are secured in spaced apart relation by means of upper and lower frame rods 16, whose reduced threaded ends 17 extend through the end pieces or uprights 10 and 11 and are secured by means of nuts 18 so as to thus form a rigid rectangular frame.

The upper and lower rods 16 of the main or outer frame pass through U-shaped upper and lower guides 19 which extend continuously along the rods with their ends projecting into the grooves of the end pieces or uprights 10 and 11 so that these U-shaped guides thus form inwardly opening grooves 20 along the outer portions of the main or outer frame for the reception of the upper and lower flanged edges 21 and 22 of the inner frame which consists of a body plate 23 adapted to be shifted endwise into the main frame through the slot 12 of the end piece or upright 11.

As shown in Figure 6 the upper and lower ends of the slotted end piece or upright 11

are grooved to receive the corresponding ends 17 of the rods 16, the nuts 18 being applied over washers 24 having angular portions disposed in the grooves as shown.

5 As seen in Figure 7 an upright brace strip 25 is proposed for disposition intermediate the ends of the main frame in case the latter is of considerable length, this brace strip having clamping members 26 10 bolted in connection with its opposite ends for embracing the upper and lower frame rods 16 and the inner frame guide strips 19 and also having at its opposite ends endwise projecting apertured lugs 27 the latter 15 of which may be utilized similar to the lugs 14 of the end pieces or uprights 10 and 11 for connecting the main or outer frame as a whole in place upon a building, motor vehicle body and the like.

20 Through the bosses 13 of the end piece or upright 11, which bosses may extend the full width of said upright as indicated at 13^a in Figures 8 and 9, are rotatable and lengthwise shiftable clamping members having 25 outer handle knobs 28 and outer offset angular portions 29, which latter may be easily shifted into and withdrawn from the slot 12 of the end upright 11 by virtue of the lengthwise and rotative movement of 30 the clamping members in the bosses. At their inner ends beyond the bosses these clamping members have heads 30, compressed between which and the inner ends 35 of the bosses are controlling springs 31 which thus serve to hold the clamping members in either the outturned inactive position shown in Figure 8 or the inturned active position shown in Figure 9 wherein their offset outer portions 29 extend into the 40 groove 12 of the end piece or upright 11 and thus serve to hold the inner frame against accidental displacement after it has been shifted endwise into the outer frame within the grooves 20 of the upper and 45 lower guides 19 and the grooves of the end pieces or uprights.

The sign panels indicated at 32 in Figures 10, 12 and 13 as well as in Figure 1, which may have suitable characters or letters, and which are interchangeable for definite relative positions within the inner frame to form the desired reading matter of the sign, are simply rectangular plates of somewhat less than half the width of the inner frame plate 23. These sign panels may be either shifted endwise into the upper and lower longitudinal grooves of the inner frame formed between the angular longitudinal edge flanges 21^a and 22^a of the plate 23 50 and the somewhat similar flanges 33 of a central longitudinal guide strip 34 secured to the plate as seen in Figures 14 and 15, or may be placed with their outer edges beneath the angular flanges 21 and 22 of the inner frame plate 23 shown in Figures 10 to 13 including

55 sive and then rocked flatwise against the forward surface of the plate by virtue of hinged clamping strips 35 along the central portion of the plate, these clamping strips being hinged upon a rod 36 centrally and longitudinally of the plate 23, secured at its ends through lugs 37. In this latter construction shown in Figures 10 to 13 inclusive, the clamping strips 35 are controlled by springs 38 engaging said strips and coiled 70 around the rod 36, which thus serve to hold the clamping strips in effective positions against accidental outward movement.

75 In this way the clamping strips 35 serve to form with the longitudinal edge flanges 80 21 and 22 upper and lower lengthwise guide grooves for the reception of the sign panels the same as are formed by the coacting flanges 21^a, 22^a and 33 in the form of the invention shown in Figures 14 and 15.

85 It is obvious that irrespective of which form of inner frame is utilized, such inner frame may be readily shifted into and out of the outer frame. In withdrawing the inner frame it is simply necessary to pull 90 out and turn the spring holders of the end piece or upright 11. The inner frame is then shifted lengthwise through the end strip or upright 11 and when it is free from the main or outer frame it is obviously an 95 easy matter to rearrange or insert new sign panels 32. The inner frame is then replaced and relocked within the outer frame by again turning the spring holders to the 100 effective position shown in Figure 9.

105 The form of the inner frame shown in Figures 10 to 13 inclusive makes it possible, however, to insert new sign panels or rearrange those already within the inner frame without withdrawing the inner frame from the outer frame and it thus becomes obvious that our invention not only provides a sign of the present type which may be easily and quickly mounted in the first 110 instance and thereafter adjusted whenever desired, but our invention further provides a sign of this type which is simple, strong and durable, in connection with which the parts may be readily renewed, and one which 115 will be simple and inexpensive both as to first cost and upkeep.

Having thus described our invention what we claim is:—

120 1. A sign of the character described including an outer frame consisting of end pieces having inner grooves, one of said end pieces also having a slot therethrough, rods rigidly connecting the end pieces in spaced apart relation, guide pieces supported on the rods between the end pieces and also presenting inner grooves, sign panels and an inner frame or holder having means to detachably support the sign panels and shiftable endwise into and out of the main frame through 125 the said slotted end piece, said holder being 130

disposed within the grooves of the side and end pieces of the main frame and said slotted end piece of the main frame having means to engage and support the holder 5 against accidental displacement.

2. A sign including a main rectangular frame having grooved side and end members and one slotted end member, a holder shiftable into the frame and into the grooves 10 thereof through said slotted end member, having angular flanges longitudinally thereof along its edges, hinged spring actuated clamping strips along the said holder inter-

mediate the angular flanges thereof and co-operating with said flanges to form surface 15 guides, and a series of interchangeable sign panels for disposition in the said guides of the holder, said slotted end piece of the frame having members shiftable into and out of its slot to removably confine the panel 20 holder in place.

In testimony whereof we have affixed our signatures.

DAVID E. SCHAFER.
JOHN W. SCHAB.
